UNITED STATES PATENT OFFICE.

FLOYD E. MACK, OF LOCKPORT, NEW YORK, AND FREDERICK R. FOSTER, OF JONESBORO, TENNESSEE, ASSIGNEES TO MACK-FOSTER CO., OF NORRISTOWN, PENNSYLVANIA, A CORPORATION OF DELAWARE.

OIL-BURNER.

1,299,491.

Specification of Letters Patent.

Patented Apr. 8, 1919.

Application filed July 18, 1918. Serial No. 245,542.

To all whom it may concern:

Be it known that we, FLOYD E. MACK and FREDERICK R. FOSTER, citizens of the United States, and residing at Lockport, in the county of Niagara and State of New York, and Jonesboro, in the county of Washington and State of Tennessee, respectively, have invented certain new and useful Improvements in Oil-Burners, of which the following is a specification.

Our invention relates to improvements in oil burners, and it consists in the constructions, combinations and arrangements herein described and claimed.

An object of our invention is to provide an oil burner intended primarily for use in cooking stoves but capable for use in furnaces equally as well, one of the principles of the invention being in the shaping of certain of the parts so that they act as deflectors with the ultimate result that a perfect circulation of the air is obtained.

Another object of the invention resides in the novel construction of the adjustable mixing chamber which consists in combination, the beveled manifold air outlets, the adjacent and coacting pan rim, and the convex surfaces of both the pan bottom and oil nozzle.

A further object of the invention resides in the formation of the ends of the manifold and the adjacent surfaces of the burner base, whereby a close contact is maintained at all times regardless of the expansion to which the manifold is subject.

Other objects and advantages will appear in the following specification, reference being had to the accompanying drawings in which:

Figure 1 is a sectional view showing the burner applied to an ordinary range,

Fig. 2 is a slightly enlarged sectional view of the burner,

Fig. 3 is a plan view of the oil pan and nozzle,

Fig. 4 is a plan view of the burner, a portion of the manifold being broken away to show the deflector on the inside,

Fig. 5 is a perspective view of the manifold, and

Fig. 6 is a perspective view of the burner base.

In carrying out our invention we provide a burner base 1 which is hollow at the ends

to form air passages 2. The inner walls 3 of the air passages 2 are inclined at an angle of approximately 60° and terminate in a bottom 4. The bottom 4 has a central prominence 5, the top of which rises above the ridges 6 which close the sides for some distance upwardly. An oil reservoir is thus formed, into which oil initially overflows when lighting the burner.

The burner base 1 in the present instance, is set upon the grate 7 of an ordinary range. In order that the passage of the air from beneath the grate may be confined to the burner, the ends and other open places around the burner, are sealed by cement 8. The air is therefore drawn through the air passages 2 in the direction of the arrows in Fig. 1.

Openings 9 near the top of each of the inclined walls 3, have crotches or manifold supports 10 on each side. As is well illustrated in Fig. 6, the openings 9 as well as the crotches 10 which are parallel with the edges of the openings, are arranged in a V-formation, and this formation plays an important function in connection with the manifold which is set in place on the crotches over the openings.

Manifold 11 has a top 12. The two parts of the manifold are fitted together and the top 12 is prevented from becoming displaced laterally on the bottom 11, by means of pins or lugs 13 on the inside. The manifold is made in the peculiar shape illustrated in Figs. 4 and 5. The open ends of the manifold are inclined downwardly at an angle to correspond with that of the walls 3 of the burner base. Likewise, the shape of each of the openings corresponds to that of the openings 9, so that when the manifold is set in place on the burner base, the respective openings will lie in substantial continuation.

The manifold is self-positioning on the burner base. This important feature is obtained directly by the shape of the manifold 100 ends and the inclination of the walls 3. Under ordinary conditions the lower points of the V-shaped manifold openings lie below the plane of the lower ends of the crotches, and the sides of the V-openings lie 105 in contact with the crotches. When the burner becomes hot, the manifold expands in all directions, and this expansion is com-

pensed for by the riding up of the surfaces adjacent to the V-openings therein, over the adjacent surfaces of the V-openings 9 in the burner base. Although the side 5 edges of the manifold move out of contact with the crotches, yet the contacting surfaces just referred to remain in engagement, and this is one of the important considerations of the invention. An air-tight joint 10 is thus always preserved since the weight of the manifold assists largely in preserving the joint.

The oil burner comprises a nozzle 14 and a pan 15. The oil burner has a threaded 15 bore and by this means is adjustable on the threaded end of the fixed oil supply pipe 16. The head 17 of the nozzle 14 is convex, and the rim of the head extends slightly beyond the main body of the nozzle. The bottom 20 of the pan 15 is likewise convex at 18, and the convexity of the bottom terminates at the base of an annular flange 19.

The flange 19 flares outwardly and the inner surface thereof coincides in inclination to the beveled edge 20 of the air outlet 21 of the manifold 11. By this arrangement, the mixing chamber retains an outlet uniform in shape throughout the adjustments of the oil pan and nozzle on the pipe 16 and 30 in respect to the manifold.

A deflector 22 located in the center of the air outlet 21, prevents the upward adjustment of the oil nozzle beyond the plane of the lower edge of the air outlet. This deflector 22 also becomes hot and aids in the vaporization of the oil as it flows out of the oil nozzle. It is important that the surfaces 35 17 and 18 be made convex as described. Flat surfaces tend to retard the flow of the oil. It has been found in practice that a flat surface will tend to permit the oil to collect in pools. This defect is remedied by the provision of the convex surfaces, which naturally cause the oil to flow downwardly in the direction of the arrows in 40 45 Fig. 2.

Most of the oil vaporizes at the head 17 of the nozzle. However, some of the oil may drop down upon the pan 15 where it 50 quickly flows over the convex bottom 18 and is rapidly vaporized. Air flowing through the manifold and out of the air outlet 21, mixes with the oil vapor in the mixing chamber, and the flame is directed upwardly 55 by the deflector formed by the similarly inclined surfaces 19 and 20.

The inclined walls 3 also act as deflectors in that they throw the heated air upwardly. Beside aiding in the vaporization of the oil, 60 the member 22 acts as a deflector for the oil at the outlet of the nozzle 14 in that it prevents the oil from being thrown up into the manifold should an extra large quantity come through the pipe 16. In this connection it is to be observed that the oil flows

from a suitably disposed supply tank 23. The tank has a pendent pipe 24 with a valve 25, by means of which the dropping of the oil into the supply pipe 16 is regulated.

70

The operation.

The two-part manifold is set in place on the inclined walls 3 of the burner base 1, where the combined V-shape and slope of 75 the manifold parts insures a tight fit over the openings 9 of the walls 3. This tight fit is maintained even when the manifold has become expanded.

Oil is permitted to overflow the flange 19 80 of the pan 15 into the reservoir at the bottom where it is lighted. When the parts become hot enough, the oil will then rise at the outlet of the nozzle 14. The flame and heated air traveling upwardly, naturally 85 cause a draft through the passes 2 and the outlet 21 of the manifold. This draft is strengthened by the confining of all of the air to the passages. Any necessary adjustment in the mixing chamber is obtained by 90 simply turning the pan 15 upwardly or downwardly on the threaded pipe 16.

While the construction and arrangement of the oil burner as herein described is that of a generally preferred form, obviously 95 modifications and changes may be made without departing from the spirit of the invention or the scope of the claims.

We claim:—

1. An oil burner comprising a manifold 100 with an air outlet, an oil nozzle adjustable in respect to the air outlet, and means bridging the air outlet having the combined functions of assisting in the vaporization of the oil upon heating thereof and acting as a deflector to prevent the throwing of the oil 105 into the air outlet of the manifold.

2. An oil burner comprising a manifold having an air outlet, a combined oil vaporizing member and deflector for preventing the throwing of oil into the air outlet, bridging the air outlet and forming a stop to limit the adjustment of an oil nozzle toward the air outlet, and an oil nozzle disposed beneath said stop.

3. An oil burner comprising a manifold with an air outlet having a beveled edge, and an oil nozzle adjustable toward the air outlet, said nozzle including a pan with an annular flange having an inner surface parallel with said beveled edge, insuring a uniform width of a mixing chamber outlet regardless of the adjustment of said oil nozzle.

4. An oil burner comprising a manifold having a air outlet with a beveled edge, an 125 oil supply pipe in fixed relationship with said air outlet, and an oil nozzle adjustable on the supply pipe and toward the air outlet, said nozzle including a head and bottom having convex surfaces for the downward 130

flow of the oil, and an upwardly flared annular flange having an inner surface parallel with that of the beveled edge, to preserve a mixing chamber outlet of a uniform width 5 regardless of the adjustment of said oil nozzle.

5. The combination of an air outlet having a beveled edge and a combined stop and deflector spanning the mouth of the outlet, 10 an oil supply pipe fixed in relationship with said deflector, and an oil nozzle adjustable on the end of the pipe and limited in its adjustment toward the air outlet by said stop, said oil nozzle comprising an oil pan 15 with a convex bottom, a head with a convex top extending beyond the body of the nozzle to cause unvaporized oil to drip to the convex bottom, and an annular flange surrounding the pan with an inner surface parallel 20 to said beveled edge.

6. Means embodied in an oil burner for deflecting the flame and hot air upwardly, comprising a manifold having an air outlet with an upwardly beveled edge, a coacting 25 adjustable oil nozzle including an upwardly inclined annular flange adjoining said beveled edge and providing an upwardly inclined mixing chamber for throwing the flame upwardly, and a burner base having 30 upwardly inclined manifold supporting ends, said inclined ends deflecting the hot air upwardly.

7. Means in an oil burner for insuring a tight joint between a manifold and a burner base regardless of the amount of expansion 35 of the manifold, comprising burner base

ends with inwardly inclined surfaces provided with openings, a manifold having corresponding openings of a V-shape and formed on a slope corresponding to the inclination of said burner base end surfaces, enabling the riding up of the ends of said manifold upon said surfaces in the expansion of the manifold and still maintaining a tight joint, and crotches at the sides of the 40 45 openings in said burner ends normally supporting the manifold.

8. An oil burner adapted to be set on a grate and surrounded by cement to cut off air, a bottom having a central prominence 50 and side ridges defining a part of an oil reservoir, inclined walls rising from the bottom and forming air passages in communication with the space beneath the grate at the ends of the burner base, said walls having 55 openings with crotches at the sides, a manifold having open ends corresponding in shape to said openings and formed on a slope to lie closely against said walls, an air outlet pendent from the manifold, with a beveled edge and a combined deflector and stop 60 spanning said opening, an oil supply pipe supported in said prominence, and an oil burner adjustable on said pipe toward said stop, comprising a pan with a convex bottom, 65 an annular flange parallel to said beveled edge, and a nozzle head with a convex surface, reaching beyond the body of the oil nozzle to permit unvaporized oil to drip on the convex bottom.
